UNITED STATES PATENT OFFICE.

FRANK BERENSTEIN, OF CHELSEA, MASSACHUSETTS, ASSIGNOR TO PANTHER RUBBER MANUFACTURING COMPANY, OF STOUGHTON, MASSACHUSETTS, A CORPORATION OF MASSACHUSETTS.

DESIGN FOR A SHOE HEEL.

Application filed December 23, 1922. Serial No. 4,701. Term of patent, 14 years.

To all whom it may concern:

Be it known that I, FRANK BERENSTEIN, a citizen of the United States, residing at Chelsea, in the county of Suffolk and Commonwealth of Massachusetts, have invented a new, original, and ornamental Design for a Shoe Heel, of which the following is a specification, reference being had to the accompanying drawing, forming a part thereof.

In the drawings Fig. 1 is a plan view of a heel, showing my new design, and Fig. 2 is a sectional view showing the studs and depressions.

I claim:

The ornamental design for a shoe heel as shown.

FRANK BERENSTEIN.
